RETURN OR COUNTERBALANCE FOR PUNCH
PRESS CONTROLS

Gustav O. Johnson, Elkhart, Ind.

Original application April 1, 1938, Serial No.
199,471. Divided and this application March
6, 1939, Serial No. 259,947

5 Claims. (Cl. 74—512)

This invention relates to improvements in return or counterbalance for punch press controls.

This is a division of my application for patent Serial No. 199,471 for improvements in Punch press controls, filed April 1, 1938.

The main object of the present invention is to provide a punch press control embodying a return or counterbalance mechanism for a punch press control actuating link, the elements of which are readily removable and quickly replaceable without stopping the machine, if such is desired or necessary.

Further objects relating to details and economies of the invention will appear from the description to follow. The invention is defined in the claims.

A structure embodying the features of my invention is illustrated in the accompanying drawing, wherein:

Fig. 1 is a perspective view of a treadle operated punch press equipped with a single-revolution control embodying the link return or counterbalance mechanism of the present invention.

Fig. 2 is an enlarged fragmentary view in side elevation illustrating the construction and arrangement of the return mechanism herein claimed.

Fig. 3 is an enlarged fragmentary view partially in section on line 3—3 of Fig. 2, further illustrating details of the construction.

In the above identified application I illustrate and describe in particular a single-revolution control means, herein designated generally 1, for a treadle operated punch press 2, which control means positively declutches the punch ram after each punching operation so as to prevent another cycle until the treadle has been allowed to return to raised position. The aforesaid control means 1 includes as a part thereof an actuating link 3 herein designated 3 having adjustably secured adjacent one end thereof a follower 4 periodically engageable by a control element 41 on the ram eccentric shaft to urge the follower to the right as viewed in Fig. 1. The link 3 extends upwardly between a pair of grooved guides or rollers 5 and is adapted to be pivoted in clockwise direction relative to the guides as the result of actuation of follower 4 by the control element 41. The follower is adjustably secured to the link by means of a set screw 42.

Intermediate the follower 4 and guides 5, the link is provided with a notch 51 engageable with the pivot pin 52 of a toggle control connection or joint 53, being disengaged from said pin by the aforesaid clockwise pivoting of the link and

being normally urged toward the pin by the counterbalance or return mechanism of the present invention, which is generally designated 54.

As described in the aforesaid parent application, when the link 3 is actuated downwardly, it breaks the toggle connection 53 and a cycle of the press operation commences. The follower 4 is engaged by control element 41 to disengage notch 51 from the pivot pin 52, whereupon the toggle connection is straightened by a counterbalance weight 6 thereon for a subsequent stoppage of the ram eccentric shaft in the manner described in the aforesaid application. For the purpose of actuating link 3 downwardly, it is connected at its lower end to a treadle 8. The counterbalance mechanism 54 of the present invention serves as means to elevate the link and counterbalance the same in counterclockwise direction as viewed in Fig. 1, when the treadle 8 is released, in order to again engage notch 51 with pivot pin 52 of the toggle connection 53 for a succeeding press operation.

As clearly illustrated in Figs. 2 and 3, the return or counterbalance mechanism of my invention consists of a pair of coil compression springs 9 interposed between a fixed abutment 10 on the press frame and an adjustable abutment 11 carried by link 3, these respective abutments being laterally offset from one another so as to permit a counterclockwise actuation of the link relative to guides 5 by the springs to urge the link against pivot pin 52, as well as an elevating of the link.

The present invention is also concerned with an improved mounting for springs 9, which enables the same to be removed and replaced readily and quickly in case of breakage or for other reason without necessarily stopping the operation of the press flywheel.

Referring in particular to Fig. 3, it will be seen that the springs are centered and held in position by pairs of pins 12, 13 on abutments 10 and 11 respectively. The tubular sleeves 14 surround the springs 9 and are crimped inwardly at 15 at the bottoms thereof in order to enable the said springs to be compressed and removed from the pins 12 by simply lifting the springs, then removed from the pins 13 by a simple movement of withdrawal. In this manner, it is apparent that the springs may be removed and replaced with a maximum of speed and a minimum of difficulty without stopping the press. The abutment 11 is readily adjustable lengthwise of link 3 by means of a clamping arm 16 and a set screw 17 carried thereby, as illustrated in Fig. 2. It is therefore possible to regulate the thrust exerted

by the springs 9 at will. Likewise, in the event it is desired to remove the link 3 entirely, this may be readily accomplished by loosening the set screws 42 and 17 and sliding the link out lengthwise.

The foregoing mechanism is a simple yet effective one for assuring an adequate actuation of the link 3 towards the left to enable the engagement thereof with the toggle mechanism when a press revolution has been completed, although it will be apparent that the advantageous features of replaceability of the springs with little difficulty recommend the construction for use in other connections.

I have illustrated and described my improvements in an embodiment which is very practical. I have not attempted to illustrate or describe other embodiments or adaptations as it is believed this disclosure will enable those skilled in the art to embody or adapt my improvements as may be desired.

Having thus described my invention, what I claim as new and desire to secure by Letters Patent, is:

1. In a press of the type described, a clutch member adapted to connect and disconnect the press with a driving instrumentality therefor, means for shifting said member into and out of operative position comprising treadle actuated link means, means for returning said link means to original position when the treadle is released comprising a fixed abutment and an abutment carried by said link means, a spring engaging said abutments, pins on said abutments for positioning and centering said spring, and a sleeve surrounding said spring and having provision for engaging and removing the same.

2. In a control means of the type described, a frame, an actuating link, treadle means for shifting said link longitudinally relative to the frame, means on said frame for guiding longitudinal movement of the link, means for returning the link to original position when released by said treadle means, comprising a pair of springs, abutments on said frame and link engaged by said springs, there being pins on said respective abutments for positioning and centering the springs, and sleeves surrounding the springs to facilitate removal thereof, and means on said link abutment

for adjusting the same and for loosening the same to permit removal of the link.

3. In a control means of the type described, a frame, an actuating link, treadle means for shifting said link longitudinally relative to the frame, means on said frame for guiding longitudinal movement of the link, means for returning the link to original position when released by said treadle means, comprising a thrust spring, abutments on said frame and link respectively engaged by said spring, there being pins on said respective abutments for positioning and centering the spring, and a sleeve surrounding the spring to facilitate removal thereof.

4. A counterbalance and return mechanism for a punch press control having an actuating link and means for shifting the link relative to the frame of the press, including means on said frame for guiding longitudinal movement of the link under the influence of the link shifting means, means for returning the link to original position when released by said link shifting means, said return means exerting a continuous counterbalancing force on the link in a lateral direction and including a pair of springs, abutments on the frame and link engaged by said springs, said abutments being laterally offset from one another whereby the springs urge the link laterally relative to the frame, pins on said abutments for positioning and centering the springs, and sleeves surrounding the springs to facilitate removal thereby by individual compression of the springs out of engagement with the pins.

5. A counterbalance and return mechanism for a punch press control having an actuating link and means for shifting the link relative to the frame of the press, including means on said frame for guiding longitudinal movement of the link under the influence of the link shifting means, means for returning the link to original position when released by said link shifting means, said return means exerting a continuous counterbalancing force on the link in a lateral direction and including a spring, and abutments on the frame and link engaged by said spring, said abutments being laterally offset from one another whereby the spring urges the link laterally relative to the frame.

GUSTAV O. JOHNSON.
